UNITED STATES PATENT OFFICE

OTTO J. MOEHLER, OF NEWARK, NEW JERSEY, ASSIGNOR TO GENERAL ELECTRIC VAPOR LAMP COMPANY, OF HOBOKEN, NEW JERSEY, A CORPORATION OF NEW JERSEY

SUPPORT MEANS

Application filed April 1, 1927. Serial No. 180,165.

The present invention relates to supporting means which are movable and which are adapted for variation in lateral dimensions to suit loads of various heights or loads having a center of gravity at different heights and at different lateral distances from the center of the support.

Various objects and advantages of the invention will be obvious from the following 10 particular description of one form of mechanism embodying the invention or from an inspection of the accompanying drawings; and the invention also consists in certain new and useful features of construction and combinations of parts hereinafter set forth and claimed.

In the accompanying drawings there is shown for purposes of illustration one form of mechanism embodying the invention, in 20 which

Fig. 1 is an elevation view showing an embodiment of the invention in the form of a portable support platform adapted to receive a cooperating extension member for increasing 25 the distance between rollers under the support.

Fig. 2 is a plan view showing the support member of Fig. 1 together with an extension member mounted thereto.

30 Fig. 3 is an elevation view of the parts shown in Fig. 2, and

Fig. 4 is an elevation view showing the support means of the invention used to carry a mercury vapor arc lamp and auxiliary apparatus therefor.

In the drawings, with particular reference to Fig. 1, the base member 1 carries at each side thereof the outwardly extending pedal 2, to which is removably attached a swivelled 40 roller or caster 4, the attaching means comprising a plate 6 carried by each of said rollers having a set of holes 8, 8 and bolts 10, 10 which pass therethrough and through corresponding holes 12, 12 in said pedals 2, 2.

45 Centrally of said base 1 is provided a standard 14 to which is mounted the mercury vapor lamp 16 which is adjustably movable vertically thereon. Auxiliary apparatus 18 for said lamp 16 is carried on said base 1.

50 Referring particularly to Figs. 2 and 3 there

is shown the frame 20 mounted about said base 1 and attached thereto by bolts 10, 10 at the holes 12, 12. Extending laterally from said frame 20 are the pedals 22, 22 to which are attached the rollers or casters 4, 4 which 55 can be those used on the pedals 2, 2 of the base 1 in Fig. 1. The use of the frame 20 to extend the distance between the supporting rollers 4, 4 is particularly useful in connection with standard support outfits which are 60 designed to carry different loads which extend to different heights, or extend laterally to different distances, or which are adjustable vertically or laterally. The support of the invention has been illustrated in connection 65 with a mercury vapor arc lamp outfit which is especially designed for use in photographic studios and which consists of one or more lamps with which are used auxiliary apparatus units which extend vertically from the 70 base 1 to the height of about two and a half to three feet, one auxiliary unit being supplied for each lamp. The lamps on these stands are in some cases used at a distance of two to four feet from the floor and in others 75 at other heights up to seven or eight feet, or more. In some cases the lamps are adjusted vertically on the standard to serve particular needs. These lamp outfits are portable and as described are mounted on rollers and for 80 that reason it is necessary to provide bases of suitable lateral dimensions to prevent overturning of the outfits during handling and to facilitate the use thereof in places where space must be economized. Accord- 85 ingly the adjustable base member of the invention has been provided as being found suitable to meet the demands of an adjustable base which can be turned out with standard lamp outfits.

90 While I have shown and described and have pointed out in the annexed claims certain novel features of the invention, it will be understood that various omissions, substitutions and changes in the forms and details of the device illustrated and in its use may be made by those skilled in the art without departing from the spirit of the invention.

I claim:

1. A portable support for supporting a 100

- load and adapted to be increased and reduced in area to conform to various loads comprising a base member, means for attaching rollers under said base member, a frame about said base member, means on said frame for cooperating with said attaching means on said base member for detachably attaching said frame to said base member, and means on said frame for attaching supporting rollers.
2. A portable support for supporting a load and adapted to be increased and reduced in area to conform to various loads comprising a base member, means adapted to the attaching of rollers under said base member, a frame about said base member, means on said frame for cooperating with said attaching means on said base member for detachably attaching said frame to said base member, and means on said frame adapted to the attaching of supporting rollers, and supporting rollers attached to said support at said second attaching means.
3. A support member having rollers or casters thereunder and adapted to be increased and decreased in area to change the distance apart of the supporting rollers or casters to accommodate different loads and particularly loads having centers of gravity at different heights, comprising, a base member, means thereon for supporting rollers or casters, a frame extending about said base member and having means for attaching it to the supporting means on said base member, and roller or caster attaching means on said frame at distances apart greater than the distance between the roller or caster attaching means on said base member.
4. A support member having rollers or casters thereunder and adapted to be increased and decreased in area to change the distance apart of the supporting rollers or casters to accommodate different loads and particularly loads having centers of gravity at different heights, comprising, a base member, means thereon for supporting rollers or casters, a frame extending about said base member and having means for attaching it to the supporting means on said base member, roller or caster attaching means on said frame at distances apart greater than the distance between the roller or caster attaching means on said base member, and rollers or casters having attaching means adapted for attachment to said support member.
5. In combination a base member, pedals extending laterally from said base member, a frame extending about said base member and detachably attached to said pedals, pedals extending laterally from said frame, and rollers or casters detachably attached to the pedals of said frame, said rollers being attachable at will directly to said base member.
6. A portable support comprising a base member, a frame extending about said base
- member, a plurality of rollers, means for attaching said frame to said base member, and means for attaching said rollers to said frame, said first mentioned attaching means being similar to said roller attaching means, whereby said frame may be eliminated at will and said rollers attached directly to said base member to reduce the area of said support.
- Signed at Hoboken in the county of Hudson and State of New Jersey this 29th day of March A. D. 1927.
- OTTO J. MOEHLER.
